Des. 240,454
Patented July 6, 1976

240,454

COMBINED PHONOGRAPH AND CARTRIDGE PLAYER

Leonard Kaye, Westfield, N.J., assignor to
Capehart Corporation, New York, N.Y.

Filed Nov. 5, 1974, Ser. No. 521,229

Term of patent 14 years

Int. Cl. D14—01

U.S. Cl. D56—4 R

FIG. 1

FIG. 2

FIG. 3

FIG. 4

FIG. 5

FIG. 6

FIG. 1 is a front, top and right side perspective view of a combined phonograph and cartridge player showing my new design;

FIG. 2 is a front elevational view;

FIG. 3 is a left side elevational view;

FIG. 4 is a right side elevational view;

FIG. 5 is a top plan view; and

FIG. 6 is a bottom plan view.

The rear of the base of the combined phonograph and cartridge player is plain and unornamented.

I claim:

The ornamental design for a combined phonograph and cartridge player, as shown and described.
